J. R. RAPLEE.
DRAWER SLIDE.
APPLICATION FILED MAY 25, 1915.

1,210,362.

Patented Dec. 26, 1916.

By

Robert Tracy, Attorney

UNITED STATES PATENT OFFICE.

JOHN R. RAPLEE, OF SHELBYNA, MISSOURI.

DRAWER-SLIDE.

1,210,362.

Specification of Letters Patent. Patented Dec. 26, 1916.

Application filed May 25, 1915. Serial No. 30,460.

To all whom it may concern:

Be it known that I, JOHN R. RAPLEE, a citizen of the United States, residing at Shelbina, in the county of Shelby and State 5 of Missouri, have invented certain new and useful Improvements in Drawer-Slides, of which the following is a specification.

This invention relates to drawer slides, and has as its object to provide a slide so 10 constructed that it will evenly guide the drawer as the same is slid open or closed and will effectually prevent sticking of the drawer.

It is one aim of the invention to so construct the guide that the same will be adapted, in the full open position of the drawer, to support the drawer bodily in advance of the desk or other article of furniture in which it is mounted, so that access may be had to 20 all portions of the said drawer.

Another aim of the invention is to so construct the slide that the drawer may be bodily removed or dismounted whenever so desired and without the necessity of removing 25 any screws or other fastening devices or employing any tools.

Another aim of the invention is to provide a novel detent device for automatically connecting the drawer supporting rail and 30 the connecting rail of the device for movement in unison when the drawer has been withdrawn a predetermined distance.

In the accompanying drawings, Figure 1 is a plan view of the guide embodying the 35 present invention applied. Fig. 2 is a perspective view, partly in section illustrating the slide. Fig. 3 is a side elevation of the slide, the supporting rail being drawn forwardly to the fullest extent. Fig. 4 is a detail transverse sectional view on the line 4—4 of Fig. 3. Fig. 5 is a longitudinal sectional view on the line 5—5 of Fig. 4, looking in the direction indicated by the arrows.

Corresponding and like parts are referred 45 to in the following description and indicated in all the views of the drawings by the same reference characters.

The slide embodying the present invention includes a guide rail 1 formed with a channel 2 which extends longitudinally thereof and the walls of which are undercut, as indicated at 3. This guide rail is provided at 50 its ends with triangular attaching plates 4 having openings 5 through which may be passed screws or other securing elements 55 which are to be driven into the front and

rear walls of the drawer compartment so as to secure the rail in place in the manner clearly shown in Fig. 1 of the drawing. The rail 1 is further provided between its ends 60 with an attaching plate 6 which may be integral therewith or secured thereto in any suitable manner and this plate is provided above and below the rail 1 with openings for the passage of screws for securing the plate 65 to the inner side of the panel of the drawer compartment.

The device embodying the present invention further includes a supporting rail which is carried by the drawer and a connecting 70 rail which slidably connects the guide and supporting rails and which is indicated by the numeral 7. This rail includes a connecting portion 8 formed at one longitudinal edge with a flange 9 occupying a plane at 75 right angles to the plane of the connecting portion 8 of the said rail and extending above and below the said portion. This flange extends from one end of the rail to a point intermediate the ends thereof, and from the point of termination of the inner end of the flange the connecting portion 8 is cut away or reduced in width, as indicated at 10. The rail 7 is formed along its other longitudinal edge and throughout its 80 entire length with a flange 11 which is parallel to the flange 9 and, as in the case of the said flange 9, extends above and below the said connecting portion 8 of the said connecting rail. By reference to the drawings 85 it will be observed that the flange 9 of the connecting rail slidably fits within the undercut walls of the channel 2 in the guide rail 1.

The drawer supporting rail is indicated 90 by the numeral 12 and is formed with a longitudinally extending channel 13 having its walls undercut, as indicated at 14, the undercut walls of the channel slidably fitting the flange 11 of the connecting rail. 100 As stated before, the connecting portion 8 of the connecting rail is cut away, as indicated at 10, and it is narrowed to such an extent that its outwardly presented edge will be flush with the outwardly presented side of the supporting rail 12. The rail 12 is mounted in a groove 15 formed in the side wall 16 of the drawer to be supported and is secured in place in any suitable manner, although preferably by means of an attaching plate 17 located at its rear end. 105 Inasmuch as the outer edge of the forward

portion of the connecting rail is flush with the outwardly presented face or side of the rail 12, the drawer may closely fit within the opening of the drawer compartment.

5 In order that the connecting slide 7 may be connected for movement with the drawer supporting slide 12, a detent 18 is pivoted as at 19 in the under side of the rail 12 and the pivot for the detent is so located that 10 the detent will be overbalanced by its portion 20 which is located at one side of the pivot so that its engaging end 21, which is located at the other side of its pivot, will have a tendency to move upwardly and in 15 engagement in a notch 23 formed in the lower edge of the flange 11 of the connecting rail at a suitable point. One wall of the channel in the rail 12 is recessed adjacent the pivot 19, as indicated at 24, and 20 the detent is provided with a pin 25 which projects laterally into the recess and, in the inactive position of the detent, seats in a notch 26 formed in the wall of the recess 24. The purpose of this pin will be pres- 25 ently explained. As the drawer is slid to open position, the rail 12 will travel along the rail 7 until the engaging end 21 of the detent reaches the notch 23 in the flange 11, whereupon the said engaging end of the 30 detent will engage the notch and thereby connect the two rails. Further movement of the drawer to open position will then serve to slide the rail 7 forwardly in the rail 1 and, in the full open position of the 35 drawer, the drawer will be located bodily beyond the drawer compartment and firmly supported in this position. Of course, upon closing movement of the drawer, the rail 12 will slide rearwardly upon the rail 7 un- 40 til the forward end of the rail 7 strikes the front 27 of the said drawer, whereupon the rail 7 will be carried rearwardly with the rail 12. Should it be desired to bodily

remove or dismount the drawer, the same is slid to full open position and the detent 45 18 is disengaged from the notch by pressing downwardly upon the pin 25, thereby permitting the rail 12 to slide forwardly from engagement with the said rail 7.

In order that the member 12 may be se- 50 curely held within the groove provided for its reception in the side walls of the drawer to be supported, the said member is formed with upper and lower flanges 27' which en- 55 gage in the undercut grooves in the walls of the main groove in the manner clearly shown in the drawings.

Having thus described the invention, what is claimed as new is:

In a drawer slide, a guide rail, a sup- 60 porting rail, a rail connecting the first-mentioned rails and having portions slid- ably engaging the said guide and support- 65 ing rails, the connecting rail being formed at its forward end and in its under side with a notch, a pawl pivotally mounted within the supporting rail and having its end at one side of its pivot arranged to engage within the said notch in the connecting rail upon sliding movement of the supporting rail in 70 one direction whereby to connect the said rails for movement in unison, the said sup- 75 porting rail being formed in its side with a recess located opposite the said end of the pawl and being provided in the bottom wall of its recess with a notch, and a pin projecting laterally from the said end of the pawl into the said recess and adapted, in the inactive position of the pawl, to seat within the said notch. 80

In testimony whereof I affix my signature in presence of two witnesses.

JOHN R. RAPLEE.

Witnesses:

S. G. PARSON,
ROY LASLEY.
